(57) **CLAIM**

The ornamental design for a duster connector, as shown and described.

DESCRIPTION

FIG. 1 is a front view of a duster connector of the invention with a handle;

FIG. 2 is a back view;

FIG. 3 is a side view, the other side view being a mirror image of the side view;

FIG. 4 is a front view of the duster connector of the invention without the handle; the back view being a mirror image of this front view;

FIG. 5 is a bottom view;

FIG. 6 is a top view;

FIG. 7 is a perspective view; and,

FIG. 8 is a perspective view of an alternate embodiment with the only difference being in proportion.

The broken lines in FIGS. 1-5 and 7-8 are for illustrative purposes and form no part of the claimed design.
